Filed Aug. 3, 1964, Ser. No. 81,142

Term of patent 14 years

(Cl. D26—12)

FIG. 1

FIG. 2

FIG. 4

FIG. 3

FIGURE 1 is a perspective view of a high voltage cross-arm attachment for a transmission line pole, showing my new design;

FIGURE 2 is a top plan view of the same;

FIGURE 3 is a front elevational view of the same; and
FIGURE 4 is a side elevational view of the same.

The broken line showing of insulators in FIGURE 1 and the broken line fragmentary showing of a transmission line pole in FIGURES 1, 3 and 4 are for illustrative purposes only.

I claim:

The ornamental design for a high voltage cross-arm attachment for a transmission line pole, as shown and described.
